UNITED STATES PATENT OFFICE.

RICHARD TURNER, OF WILKES-BARRÉ, PENNSYLVANIA.

GRATE.

SPECIFICATION forming part of Letters Patent No. 310,097, dated December 30, 1884.

Application filed March 12, 1884. (No model.)

To all whom it may concern:

Be it known that I, RICHARD TURNER, a citizen of the United States, and a resident of Wilkes-Barré, in the county of Luzerne and State of Pennsylvania, have invented certain new and useful Improvements in Grates; and I do hereby declare that the following is a full, clear, and exact description of the invention, which will enable others skilled in the art to which it appertains to make and use the same, reference being had to the accompanying drawings, which form a part of this specification, and in which—

Figure 1 is a top view of my improved grate. Fig. 2 is a perspective view of the same. Fig. 3 is a perspective view of one of the grate-bars, which is provided with vertical transverse wings or projections; and Fig. 4 is a cross-sectional view taken on line $x x$, Fig. 1. 20 Similar letters of reference indicate corresponding parts in all the figures.

My invention has relation to that class of grates in which the bars are given a reciprocating back and forward motion by means of suitable mechanism; and it consists in the improved construction and combination of parts of a grate of the above-mentioned class, as will be hereinafter more fully described, and particularly pointed out in the claim.

30 In the accompanying drawings, A A and B B represent the grate-bars, the construction of which will be hereinafter fully explained. The grate-bars A A are supported upon the sliding cross-pieces C C, while the bars B B, which alternate with the bars A A, are supported upon the sliding cross-pieces D D. These cross-pieces slide upon guides or ways E E on the inner side of a main frame, F. In the forward end of this frame F are journaled 40 the ends of a rock-shaft, G, adapted to be operated by means of a handle, G', and provided both upon its upper and lower edges with two lugs or projections, H H. To the upper lugs of the rock-shaft are pivotally secured the forward ends of two pitmen, I, the rear ends of which are secured to the forward sliding cross-piece of the bars A A, while to the lower lugs or projections of the rock-shaft are pivotally secured the forward ends of two longer pitmen, J J, the rear ends of which are secured

to the rear sliding cross-piece of the bars B B. The object of this arrangement will be hereinafter set forth.

A A and B B indicate the two sets or series of grate-bars, which are arranged upon their sliding supports alternately with each other, as will be readily understood by reference to the drawings, having pairs of downwardly-projecting clamping-lips A'' and B'', which straddle and clamp the sliding cross-pieces 55 and allow each grate-bar to be moved separately without disturbing the remaining ones.

The grate-bars A, one of which is shown in detail in Fig. 3 of the drawings, are each provided upon its upper edge or face with a series of forwardly-inclined teeth, A', and also has cast upon it a number of vertical transverse wings or projections, A'', of such a width as to extend entirely across the space between the sides of the bars A and the smooth sides 65 of the bars B B. These bars B B are cast with a series of teeth, B', upon their upper edges, and are placed upon their sliding supports in such a manner that their teeth incline in the opposite direction to those of the alternating bars A A.

From the foregoing description, taken in connection with the accompanying drawings, the construction of my improved grate will readily be understood without requiring further explanation. It will be seen that when the rock-shaft G is oscillated by its handle G' the two sets of grate-bars will, through the intervening mechanism previously described, be moved backward and forward in opposite directions—that is to say, when the bars A are moved backward the bars B will be moved forward, and vice versa. The vertical transverse wings of the bars A are placed at such a distance apart that one pair of wings on the 75 forward stroke of the said bars will reach the point touched by the next pair of wings on the backward swing of the bars, thereby passing over every point between the smooth sides 80 of the bars B B.

95 By constructing the two sets of bars with teeth inclined in opposite directions, and by operating the bars in the manner described, the ashes in the lower portion of the stove will be thoroughly agitated and shaken down, 100

while the vertical transverse wings of the bars A A will most effectually grind and break up all clinker which may fall between the bars.

I am aware that reciprocating grate-bars 5 are not broadly new, and that such grate-bars have been made with teeth or serrations upon their upper edges inclined in opposite directions upon alternate bars, and I do not wish to claim such constructions; but

10 I claim—

In a grate having reciprocating bars, the combination of the bar-supporting frame formed with longitudinal ways upon the inside of its sides, cross-bars sliding with their ends upon

the said ways, means, as shown, for sliding 15 said cross-bars, and grate-bars having pairs of downwardly-projecting lips upon their under sides straddling and clamping the cross-bars, as and for the purpose shown and set forth.

In testimony that I claim the foregoing as 20 my own I have hereunto affixed my signature in presence of two witnesses.

RICHARD ^{his} X TURNER.
